UNITED STATES PATENT OFFICE

2,185,921

HOOK

Harold Duncan McNaught, Vancouver, British Columbia, Canada

Application September 15, 1937, Serial No. 164,059

2 Claims. (Cl. 24—123)

This invention relates to improvements in hooks and has particular reference to a hook for use in the logging industry where it is desired to hook on to the end of a cable and to later release this 5 hitch.

A further object is to produce a device of this character which is economical to manufacture, easy to use, and one which will not become jammed in use.

10 A further object is to produce a device of this character which may be easily snaked through brush without the danger of becoming caught therein.

Other objects and advantages will be apparent 15 during the course of the following description.

In the accompanying drawing forming a part of this specification and in which like numerals are employed to designate like parts throughout the same:

20 Fig. 1 is a front elevation of my device; Fig. 2 is a side elevation of Fig. 1;

Fig. 3 is a vertical cross section showing the lock in elevation;

Fig. 4 is an end view of Fig. 2;

25 Fig. 5 is a side elevation of the lock per se; Fig. 6 is a front elevation of the latch per se; and

Fig. 7 is a bottom plan view of Fig. 5.

In the logging industry it is common to employ 30 long cables and fasten about the logs over hooks through snatch blocks; and in order to pass the cable through these various devices, it is necessary that the end thereof be comparatively free.

Therefore, it is necessary to prepare the end of 35 the cable by anchoring thereon a projection or nipple of slightly greater outside diameter than the diameter of the cable. In order to secure this enlargement on the cable to a fitting, which fitting may be attached to any piece of apparatus

40 desired, I employ a housing 5 having an opening 6 and a recess 7. Within this recess I pivot a lock, designated as a whole by the numeral 8. The lower end of the casting 5 is bifurcated, as shown at 9, and a ledge 11 is formed adjacent

45 to the lower end of the bifurcation. I have shown a cable at 12, having a head 13 secured thereto, the outer diameter of which is slightly greater than the diameter of the cable 12. This head 13 is adapted to rest upon the ledge 11 when

50 the cable extends through the bifurcated portion 9. As the slot 14, forming the bifurcation, is of less width than the diameter of the head 13, it will be apparent from Fig. 1 that the head cannot slide out of the device while in the position at the bottom of the recess 7. In order to maintain the connection, the lock 8, when in the position of Figs. 1 and 3, closes the widest diameter

of the recess 7 and is hinged at 16; and in order to keep the same in closed position, I provide a latch 17 normally held downwardly by a spring 18 so that the nose 19 of the latch will rest behind the lugs 21 formed on the bifurcated sections of the housing. A bolt 22 passes through the opening 23 in the latch and serves to hold the same in place and against accidental misplacement, yet permits the necessary movement of the latch. 5

10 It will thus be seen that I have produced a device which will accomplish all the objects above set forth.

15 It is to be understood that the form of my invention herewith shown and described is to be taken as a preferred example of the same and that various changes relative to the material, size, shape and arrangement of parts may be resorted to without departing from the spirit of the invention or the scope of the subjoined claims. 20

Having thus described my invention, I claim:

1. In a logging hook of the class described, comprising a housing having a recess formed therein, a portion of said housing being bifurcated, a ledge formed in said bifurcation and capable of receiving a headed cable, the head of which is adapted to normally rest upon said ledge, a pivoted lock mounted in said housing and capable of swinging into the bifurcation thereof and flush with the outer face of the 30 housing, lugs extending from the bifurcated sections of the housing, and a spring urged latch mounted in said lock and capable of passing over said lugs to latch the pivoted lock together with the housing, and said lock having an extension carried by the inner lower end thereof and capable of abutting against the head of said cable to lock the same within said housing. 35

2. In a logging hook of the class described, 40 comprising a recessed housing capable of receiving a headed cable, the outer portion of said housing being bifurcated, a head receiving and supporting ledge formed in said bifurcation and capable of receiving and retaining the head of 45 said cable, a pivoted lock mounted in said housing and adapted to swing into the bifurcation thereof and flush with the outer face of said housing, lugs extending from the bifurcated sections of the housing, a spring urged latch mounted in said lock and capable of passing over and behind said lugs to latch the pivoted lock together with the housing, said latch member being slotted, and a retaining bolt extending through the lock and through the slotted section of said latch 50 member. 55

HAROLD DUNCAN McNAUGHT.
